UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,386, dated June 12, 1888.

Application filed May 18, 1888. Serial No. 274,313. Term of patent 3½ years.

To all whom it may concern:

Be it known that I, JENNIE SHEILS, of the city, county, and State of New York, have invented and produced a new and original Design 5 for a Pattern of a Lady's Costume; and I do hereby declare that the engraved prints accompanying this specification convey to any one accustomed to using paper patterns a clear understanding of how a garment made up by 10 the pattern will appear.

The design shows a round waist and a round walking-skirt. The skirt displays a drapery falling in full water-fall fashion to the edge at the back and in a full tablier nearly to the 15 edge in front, the tablier separating in a long V at the left side of the front, and displaying draping plaits at the top and above the V and

loopings in either side over the hip. The waist displays surplice fronts lying in soft folds from the shoulders to the lower edge, 20 crossing below the bust, and flaring over high-necked fronts above the bust, a close-fitting back, a belt, a standing collar, and sleeves reaching in full puffs below the elbows and meeting the top of long close-fitting cuffs. 25

What I claim as my invention, and desire to secure by Letters Patent, is—

The design for a lady's costume, as shown in the engraved prints accompanying this specification.

JENNIE SHEILS.
